CLAIM

The ornamental design for a twist pool cue, as shown and described.

DESCRIPTION

FIG. 1 is a side elevational view of a twist pool cue of my design, the broken line showing of the top portion being for illustrative purposes only and forming no part of the claimed design;

FIG. 2 is an enlarged side elevational view thereof;

FIG. 3 is a side elevational view of FIG. 2;

FIG. 4 is another side elevational of FIG. 2;

FIG. 5 is a bottom plan view of FIG. 2;

FIG. 6 is a top plan view of FIG. 2; and,

FIG. 7 is an enlarged to plan view of FIG. 6.
